CRYSTAL CONTROLLED OSCILLATOR
CIRCUITS

Clarence W. Hansell, Port Jefferson, N. Y., assignor to Radio Corporation of America, a corporation of Delaware

Application March 14, 1932, Serial No. 598,566

5 Claims. (Cl. 250—36)

In Fig. 3 of Cady United States Patent 1,472,583 there is described an efficient crystal controlled oscillator. However, when this circuit is used it is found that the crystal does not have the maximum possible effect in controlling the frequency of the oscillations and there is an undesirable tendency for spurious oscillations to develop, the frequencies of which are not controlled by the crystal.

10 In effect the crystal in the circuit shown in Cady's Fig. 3 is a narrow band pass filter, through which the energy fed back to the grid to sustain oscillations must pass, and it is intended that sufficient energy be fed back to sustain oscillation only at frequencies near the resonant frequency of the crystal. Since, in Cady's circuit, the grid of the tube and the grid leak resistance have inherently a very high impedance, the crystal can not effectively reduce the feed back to the grid at undesired frequencies unless these frequencies are rather far removed from the resonant frequency of the crystal. The crystal acts like a series tuned electrical circuit, shunted by the dielectric capacity between the electrodes, 25 and so long as the grid circuit impedance is high the resonance curve of frequency versus feed-back to the grid is very much broader than the resonance curve of the crystal itself and the crystal cannot prevent frequency variations over 30 a relatively broad band.

As I make, according to my present invention, the grid to cathode impedance low so that the crystal supplies energy to a relatively low impedance circuit, the frequency band in which there is sufficient feed-back to the grid to sustain oscillations will be greatly reduced and the crystal will control the frequency of oscillations much more closely. This action is more fully explained in my patent application, application 40 No. 540,310, filed May 27, 1931.

Accordingly, to make the system more immune from spurious oscillations and to make the crystal more effective in controlling the frequency of the oscillator are the principal objects of my present invention. To accomplish this I place a relatively low alternating current impedance between the grid and filament of the vacuum tube. This low impedance, which is preferably a relatively small resistance with a series connected direct current blocking condenser as indicated by 30a and 32 in Fig. 1, discourages spurious oscillations which might take place by virtue of any undesired coupling from the anode to grid circuits of the tube. For example, there will be feedback 50 through the plate to grid dielectric capacity of

the tube which is often sufficient to set up spurious oscillations independent of the crystal in Cady's original circuit, particularly in oscillators designed to work at rather high frequencies.

By inserting the low impedance between grid 60 and filament of the tube I greatly reduce the voltage which can be set up on the grid, by a given value of alternating current voltage on the anode, through any undesired coupling such as that through the anode to grid dielectric capacity. As 65 a result the probability of spurious oscillations taking place, which are not controlled by the crystal, is very greatly reduced.

At the same time the A. C. voltage which can be transferred from anode to grid through the 70 dielectric capacity between the crystal electrodes is also greatly reduced and spurious oscillations from this source of coupling are also prevented.

If the desired feed-back through the crystal is considered it will be noted that the effect of this 75 feed back is also reduced so that somewhat greater coupling between coils 18 and 22 in Fig. 1 is required. However, the reduction in feedback through the crystal is much less for the resonant frequency than for frequencies somewhat off resonance for the crystal. Consequently, by properly adjusting the feedback coupling I obtain a condition where sufficient coupling to maintain oscillations is obtained only for frequencies very 80 near the resonance frequency. In this case the 85 crystal becomes a more controlling factor in the circuit and therefore, much greater frequency stability is obtained.

I have found that crystals vary greatly in their constants not only at different frequencies but 90 also for crystals ground to operate at the same frequency. A representative crystal ground for 100 kilocycles and mounted in its holder may be an effective series resistance on the order of 100 ohms and effective equivalent inductive and 95 capacitive reactances of several megohms. In such a case the effective impedance added between grid and filament of the tube should also be on the order of magnitude of 100 ohms. However, due to the great variations between crystals I prefer 100 to make the impedance, as well as the feed back coupling variable so that adjustments may be made to suit individual crystals. Accordingly a further object of my invention is to permit 105 adjustments for optimum operation by making the impedance variable.

My invention is more fully described in connection with the accompanying drawing wherein; Fig. 1 illustrates a preferred form of my present invention; and

Fig. 2 illustrates a somewhat modified form utilizing a screen grid tube;

Turning to Fig. 1, I have indicated an electron discharge device or vacuum tube 2 having a cathode 4 energized through transformer 6 with alternating heating currents. By means of the condenser network 7 and ground connection 8, symmetry of the heating circuit is insured, eliminating to a desired degree, possible modulation which 10 would otherwise occur due to the alternating E. M. F. applied to the filament heating circuit. Preferably the tube should be one designed especially for alternating filament heating current. Also direct heating current may be used. Between the cathode 4 and grid or control electrode 10 there is connected a piezo-electric frequency controlling crystal 12 as well as a parallel tuned circuit 16.

As in the Cady circuit referred to, some feed back occurs through the inter-element capacity of the tube 2 between plate or anode 14 thereof and the grid 10 as well as through the feed back or tickler coil 18. It is preferable that electrostatic shielding 20 be provided between the coil 18 and the inductance coil 22 of tunable circuit 14 as well as providing for the grounding of the direct current end of the tickler coil 18 by means of condenser 24. This reduces undesired capacity coupling which might cause spurious oscillations. Grid bias is provided by the grid leak resistor 26 effectively in shunt with the capacity formed by the electrodes of piezo-electric frequency controlling crystal 12.

As so far described, the system, in general, may 35 be made to act as a reasonably good crystal controlled oscillator. However, at certain frequencies, there will be a tendency to generate spurious oscillations determined by the electrical constants of the circuit, the crystal being considered 40 simply as a di-electric rather than a piezo-electric crystal. To eliminate this tendency to oscillate at spurious frequencies I connect across the grid and cathode circuits at points A and B a low 45 impedance which may be in the form of a resistor 30a in series with a direct current blocking condenser 32.

Now, should there be any tendency for the circuit to oscillate at some parasitic or spurious frequency, those undesired frequencies will be bypassed by the low impedance between the points 50 A and B, and no energy of spurious frequencies will occur in the output circuit so designated on the drawing. However, at the natural frequency of the crystal, the crystal acts as a series tuned 55 circuit, thereby presenting a path of low impedance relative to that between the points A and B and thereby causing relatively large feed back to the grid 10 from anode 14 through the coupling between coils 18 and 22. This feed back will 60 cause building up of voltages of desired frequency across the grid and filament and thereby cause energy of desired frequency to appear in the output circuit.

The purpose of the condenser in the series combination of low resistor 30a and condenser 32 connected across points A and B given in Fig. 1 is to prevent a reduction in the direct current impedance of the grid leak resistor. The grid leak resistor may be replaced by the series combination 65 of a source of potential and an impedance to prevent the flow of alternating current therein the impedance being, for example, a choke coil or resistor.

Fig. 2 illustrates a modification wherein the 70 plate circuit coil 18 is tuned by means of a vari-

able condenser 40 and wherein the crystal 12 is placed on the otherwise grounded side of the parallel tuned circuit 14. To prevent interelectrode feed back, tube 2 is chosen of the screen grid type having a screen grid 42. For better 80 frequency stability and as an added refinement, the cathode 4 may be energized from a direct current potential circuit diagrammatically indicated at 44 though tubes are now available which 85 equally well, for this purpose, allow of the use of alternating heating current. Condensers 24 and 25 of Fig. 2 are, of course, the usual by-pass radio frequency condensers. Also in Fig. 2, shielding 20 is preferably used to prevent capacitive feed-back from anode to grid circuits and may be 90 connected to the screen grid 42 through the medium of by-passing condenser 43. It will be found in the circuits shown in Figs. 1 and 2, that by 95 suitable adjustment of the tuning of the circuits, feed back through the inductive coupling may be in either the normal direction or it may be reversed so as to ordinarily be degenerative and still the circuit will operate under crystal control. This may be explained by virtue of the fact that 100 despite the degenerative feed back, suitable tuning of the grid circuit, or of anode and grid circuits will alter the phase of the voltages fed to the control grid 10 of tube 2 of Fig. 2, such that they are sufficiently near the correct phase to 105 produce oscillations at a frequency near the resonant frequency of crystal 12. However the frequencies generated with the feed back in one direction or the other will ordinarily be slightly different and usually on opposite sides of the exact 110 crystal resonant frequency.

Here also in Fig. 2, the impedance formed by 115 resistor 30 and large by-pass condenser 32 is low for undesired frequencies. However, for energy of a frequency corresponding to that of the crystal 12, the crystal 12 also acts as a circuit of low impedance and passes current from the parallel tuned circuit 14 at the desired frequency. Consequently, sufficient voltage of the desired frequency is built up on the grid 10 of tube 2 so as 120 to produce in the output leads 50 oscillations only of a frequency corresponding closely to that of a crystal.

The condenser 52 is merely a blocking condenser which allows passage of the high frequency energy generated but prevents passage of 125 the direct current voltage applied to the plate or anode 14.

In Fig. 2 where the crystal 12 has been placed between ground and one terminal of parallel tuned circuit 14 there are obviously some advantages in the mechanical construction of the oscillating system described.

Resistor 50 is the usual screen grid biasing resistor, and, choke 52 and source 54 maintain suitable control grid bias on grid 10.

It is to be noted, advertizing to Fig. 1, that resistor or impedance 30a has been made variable so that as already pointed out, it may serve for crystals having different effective series resistances.

Having thus described my invention, what I claim is:

1. A vacuum tube oscillation generator comprising a vacuum tube having a filament, a grid and a plate, a piezo-electric crystal in series with a parallel tunable circuit connected between said grid and said filament, and, a relatively low resistance, of the order of magnitude of the series resistance of the crystal at resonance, connected effectively across said grid and filament whereby 145 150

- only oscillations of a frequency corresponding to the natural frequency of said piezo-electric are generated by said electron discharge device. 80
2. A crystal controlled oscillation generator comprising an electron discharge device having an anode, a cathode and a control electrode, the series combination of an electro-mechanical vibrator of relatively constant frequency and a high impedance, connected between said control electrode and cathode, a relatively low resistance, of the order of magnitude of the series resistance of the crystal at resonance, connected effectively across said grid and cathode, and means for establishing feedback between the anode and control electrode of said device whereby oscillations corresponding to the frequency of said electro-mechanical vibrator are generated by said device. 85
3. In apparatus of the character described, a vacuum tube having an anode, a cathode and a control electrode, a parallel tuned circuit and a piezo-electric crystal connected in series, the said series combination being connected between said control electrode and cathode, biasing means connected across said control electrode and cathode, a relatively low resistance effectively connected across said cathode and control electrode, said relatively low resistance being of the order of magnitude of the series resistance of the crystal 90
5. A vacuum tube oscillation generator comprising a vacuum tube having a filament, a grid and a plate, a piezo-electric crystal in series with a parallel tunable circuit connected between said grid and said filament, and, a relatively low resistance, of the order of magnitude of 100 ohms, connected effectively across said grid and filament whereby only oscillations of a frequency corresponding to the natural frequency of said piezo-electric are generated by said electron discharge device. 100
